UNITED STATES PATENT OFFICE.

HOWARD PARKER, OF NASHUA, NEW HAMPSHIRE.

REEL-DRUM OR THE LIKE.

1,015,244.

Specification of Letters Patent.

Patented Jan. 16, 1912.

Application filed May 23, 1910. Serial No. 562,858.

To all whom it may concern:

Be it known that I, HOWARD PARKER, a citizen of the United States, and a resident of Nashua, in the county of Hillsboro, State 5 of New Hampshire, have invented certain new and useful Improvements in Reel-Drums or the Like, of which the following is a specification.

The object of the invention is to produce 10 a drum such as is used for paper reels and for other purposes which has a novel and advantageous construction.

Referring to the drawings: Figure 1 is a side view of a reel embodying my invention, 15 parts being broken away to show my construction. Fig. 2 is an end view thereof.

The drum comprises two or more spiders 10—10 mounted on a shaft 15 on which strips of wood 20 or other suitable material are 20 laid lengthwise and held in place by metal binding blocks 25 which are located between adjacent strips, and are adjustably secured to the spiders by studs 30. By preference the edges of these binding blocks are oppositely inclined as illustrated in Fig. 2. As 25 illustrated the strips are square in cross section, and the blocks have a slight movement toward and away from the spiders. When the strips and blocks are assembled the studs 30 are screwed down to securely fasten the strips in place. Then the surface is turned down to finished shape.

I do not desire to be understood as limited

in the use to which drums made in accordance with this invention can be put, nor to 35 the precise details of construction shown and described.

I claim as my invention:—

1. An article of the character described comprising a plurality of spiders, strips of 40 suitable material laid lengthwise thereon and spaced apart, binding blocks located between adjacent strips, and means for moving said binding blocks toward said spiders.

2. An article of the character described 45 comprising a plurality of spiders, strips of suitable material laid lengthwise on and extending from one spider to the other, said strips being spaced apart, binding blocks located between adjacent strips and studs passing through said blocks and having threaded 50 engagement with said spiders.

3. An article of the character described 55 comprising a plurality of spiders, strips of suitable material laid lengthwise on and extending from one spider to another, said strips being of square cross section, binding blocks located between adjacent strips the edges thereof being oppositely inclined and means for moving said binders toward said 60 spiders.

HOWARD PARKER.
